MOUNTING TAPE FOR SEPARABLE
FASTENERSDavis Marinsky, Bronx, N. Y., assignor to White-
hall Patents Corporation, Bronx, N. Y., a cor-
poration of New York

Application June 26, 1935, Serial No. 28,396

10 Claims. (Cl. 139—384)

This invention relates to separable fastener devices employing stringers having interengaging links or elements with a slider movable along said elements to couple and uncouple the same and more particularly to the mounting tape or tapes of stringers of this class; and the object of the invention is to provide a tape comprising a unitary woven body so fashioned as to provide a relatively wide elastic or extensible portion and one or more non-elastic portions to which the coupling links or elements are secured and which also provides means for attaching the tape to a suitable support; a further object being to provide a tape of the class described wherein both side edge portions of the tape include the non-elastic portions, and further wherein the non-elastic portion may be employed intermediate the side edges of the tape; a still further object being to provide a fastener device of the class described with unitary tapes involving elastic members whereby a yieldable coupling is provided between opposed edges of a garment or other article to be coupled together by said fastener; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a detail view of a part of a fastener made according to my invention.

Fig. 2 is a cross sectional view indicating one method of mounting a fastener in connection with opposed supports.

Fig. 3 is a view similar to Fig. 2 showing another method of mounting the device in connection with supports.

Fig. 4 is a perspective and sectional view diagrammatically illustrating a modified form of stringer; and.

Figs. 5 and 6 are views similar to Fig. 4 showing other modifications.

In the use of separable fastener devices of the class under consideration in connection with various articles of apparel and in fact, in connection with other articles of manufacture, it is at times desirable to provide means for yieldably mounting the fastener device in connection with its opposed supports to provide rela-

tive movement of the supports one with respect to the other, for example, in the use of devices of the kind under consideration in connection with shoes, overshoes and other footwear, and also on corsets, corselets, brassières and similar or other garments or articles of apparel to compensate for body movement and to provide a non-binding mounting of the garment upon the wearer, it being further understood that a fastener of this type will also find its usefulness in other articles of manufacture wherein it is desirable to provide means to compensate for stresses or strains to which the article may be subjected.

In Fig. 1 of the drawing, I have indicated a part of a separable fastener employing stringers 10, 10a, each consisting of a mounting tape or strip 11, 11a, to one edge portion of which are attaching coupling links or elements 12, 12a. At 13 I have indicated a rider or slider mounted to move longitudinally of the links to couple and uncouple the same, a finger piece or pull 14 being provided to facilitate the operation of the slider. The coupling links or elements 12, 12a may be of any desired form and construction and fashioned from any desired material, and may, if desired, be in the form of individual die castings or molded bodies formed directly upon the tapes 11, 11a.

In carrying my invention into effect, I construct the mounting tape or tapes of the fastener device from a single or unitary body which is so fashioned or woven as to provide a non-extensible or non-elastic edge portion 15 including a corded or beaded edge 15a and a wire insert 15b exposed through at least one edge of the tape longitudinally thereof to contact all of the links 12, 12a which are mounted on the corded or beaded edge 15a to facilitate the electroplating of said links. Extending outwardly from the portion 15 is a relatively wide extensible or elastic portion 16 woven integrally with the portion 15. The portion 16 is so woven as to provide yielding or extensible characteristics, especially in a direction transversely of the strip or may include in the weave elastic elements to provide the desired yielding or extensible characteristics to the tape.

By constructing a tape in accordance with the structure above described, the non-extensible edge portion 15 may be made strong and durable facilitating the attachment of the coupling links or elements therewith and to provide a secure and positive mounting of the elements thereon and at the same time providing a mounting edge

portion which will adapt the tape for use in the production of die cast or molded links or elements.

In Fig. 2 of the drawing, I have indicated one manner of attaching the stringers to opposed supports which consists in attaching the tapes 11, 11a to opposed supports 17, 17a as at 18, 18a, it being apparent that the outer side edges of the tapes or the elastic or yieldable portions 16 thereof are attached to provide, by virtue of the transverse extensibility of the mounting tapes movement of the supports 17, 17a toward and from each other. When the fastener is not subject to stress or strain, the adjacent edges of the supports 17, 17a will be maintained in close proximity to each other.

In Fig. 3 of the drawing, I have shown a slight modification in the manner of mounting the fastener to the supports 17, 17a which consists simply in including an inner facing or lining portion 19, 19a which is attached to the tapes 11, 11a by the same stitching as at 18, 18a. This construction forms what might be termed pockets longitudinally of the adjacent edges of the supports 17, 17a in which the fastener is yieldably mounted, it being understood that the slider 13 is free to move longitudinally of the pocket or pockets.

In Fig. 4 of the drawing, I have shown a detail view of a modified form of mounting tape or strip that I may employ which consists of two non-extensible edge portions 20, 21 and an intermediate elastic or extensible portion 22. The portion 20 has a beaded edge 20a for the attachment of the links or elements thereto and this beaded portion may also include the wire insert 20b which may be employed as a reinforcing means or as a means for facilitating the electro-plating of the links in accordance with the teachings defined in a prior application filed by Louis H. Morin, September 8, 1934 and bearing Serial Number 743,256. With the construction shown in Fig. 4, the non-extensible portion 21 will provide a more rigid and secure mounting of the tape in connection with the support, it being understood that the stitchings or other means of attachment will be passed through the portion 21.

In Fig. 5 of the drawing, I have shown another form of strip consisting of two non-extensible edges 23, each being beaded as seen at 23a and including the wire inserts 23b. Intermediate the portions 23 is an elastic or extensible portion 24. This type of strip may be used in connection with a multiple or dual fastener, that is to say, one employing two sets or a pair of interengaging links. It is understood in this connection that the elastic portion 24 may be varied in width to suit the particular article in connection with which the device is employed and may, in some cases, constitute a considerable part of a garment, especially in the art of corsets, corselets, girdles and like garments. One of the beaded edges 23a need not necessarily include the wire insert, in which event, the beaded edge will be used solely as a means of attachment to a garment. However, where the question of plating is not a factor, the wire inserts need not necessarily be employed in the tapes 70 or strips.

In Fig. 6 of the drawing, I have shown another form of tape having non-extensible edge portions 25 similar to the edge portions 23 in the structure in Fig. 5, the only difference between 75 the structure shown in Fig. 6 and that shown

in Fig. 5 being that two extensible or elastic portions 26, 26a are employed which are subdivided by a non-extensible intermediate portion 27 which may simply form a part of a garment, in which event, the width thereof will depend entirely upon the desired spacing required between the coupling ends controlled by the edge portions 25 or the portion 27 may simply constitute a strip providing means for attachment of a dual fastener to a suitable support, the stitchings or other fastening means passing through the non-extensible or reinforcing portion 27.

From the foregoing, it will appear that my improved mounting tape or strip for separable fasteners of the kind under consideration will adapt the fastener to many varied uses wherein the desirability of providing a yieldable coupling between two supports is a factor or advantageous to the more comfortable arrangement of a garment upon the body of a wearer or in compensating for stresses and strains between two supports coupled together by my improved fastener. While certain uses of the invention have been herein indicated, these are merely illustrative of other uses to which the device may be applied.

Having fully described my invention, what I claim as new and desire to secure by Letters Patent, is:

1. A tape for separable fasteners of the class described comprising an elongated strip of fibrous material, consisting of a wide freely extensible or yieldable portion and a narrow non-extensible side edge portion having a dense uniform rib weave throughout the length of said strip and contrasting in structure to the weave of the first named portion of said strip to provide a strong and durable edge portion, the free edge of said side edge portion being beaded and including a wire extending longitudinally of said edge and interwoven therewith, and said wire being exposed through the outer surface of the strip at close intervals throughout the length thereof.

2. In stringers for separable fasteners of the class described, a mounting tape consisting of a unitary woven body of fibrous material woven to form a uniform, non-extensible, strong and durable rib portion extending longitudinally of one edge of the tape and to which the coupling links or elements of the stringer are attached, a relatively wide elastic or extensible portion extending from said non-extensible portion in the direction of the other side edge of said mounting tape, the first named edge portion of the tape being beaded, and a wire interwoven with said edge portion and extending longitudinally thereof, said wire being exposed at the outer surface of the strip at close intervals.

3. In stringers for separable fasteners of the class described, a mounting tape consisting of a unitary woven body of fibrous material woven to form a uniform non-extensible, strong and durable rib portion extending longitudinally of one edge of the tape and to which the coupling links or elements of the stringer are attached, a relatively wide elastic or extensible portion extending from said non-extensible portion in the direction of the other side edge of said mounting tape, the first named edge portion of the tape being beaded, a wire interwoven with said edge portion and extending longitudinally thereof, and the other side edge of said tape including a non-extensible edge portion arranged

longitudinally thereof said wire being exposed at the outer surface of the strip at close intervals.

4. In stringers for separable fasteners of the class described, a mounting tape consisting of a unitary woven body of fibrous material woven to form a uniform non-extensible, strong and durable rib portion extending longitudinally of one edge of the tape and to which the coupling links or elements of the stringer are attached, a relatively wide elastic or extensible portion extending from said non-extensible portion in the direction of the other side edge of said mounting tape, the first named edge portion of the tape being beaded, a wire interwoven with said edge portion and extending longitudinally thereof, the other side edge of said tape including a non-extensible edge portion arranged longitudinally thereof, and the tape including intermediate the edge portions thereof a longitudinal non-extensible portion dividing the extensible part of the tape into a plurality of transversely spaced portions.

5. A tape for separable fasteners of the class described comprising an elongated strip of fibrous material, consisting of a wide freely extensible or yieldable portion and integrally woven therewith a narrow non-extensible side edge portion having a dense uniform rib weave throughout the length of said strip and contrasting in structure to the weave of the first named portion of said strip to provide a strong and durable edge portion.

6. A tape for separable fasteners of the class described comprising an elongated strip of fibrous material, consisting of a wide freely extensible or yieldable portion and integrally woven therewith a narrow non-extensible side edge portion having a dense uniform rib weave throughout the length of said strip and contrasting in structure to the weave of the first named portion of said strip to provide a strong and durable edge portion, and the free edge of said side edge portion being beaded.

7. A tape for separable fasteners of the class described comprising an elongated strip of fibrous material, consisting of a wide freely extensible or yieldable portion and integrally woven therewith a narrow non-extensible side edge portion having a dense uniform rib weave throughout the length of said strip and contrasting in structure to the weave of the first named portion of said strip to provide a strong

and durable edge portion, and the side edge of the first named extensible portion of the strip having integrally woven therewith a narrow non-extensible portion extending throughout the length of said strip.

8. A tape for separable fasteners of the class described comprising an elongated strip of fibrous material, consisting of a wide freely extensible or yieldable portion and a narrow non-extensible side edge portion having a dense uniform rib weave throughout the length of said strip and contrasting in structure to the weave of the first named portion of said strip to provide a strong and durable edge portion, the side edge of the first named extensible portion of the strip having a narrow non-extensible portion extending throughout the length of said strip, and another extensible portion integrally woven with and extending longitudinally of said strip in spaced relation to said first named extensible portion.

9. In stringers for separable fasteners of the class described, a mounting tape consisting of a unitary woven body of fibrous material woven to form a uniform non-extensible, strong and durable rib portion extending longitudinally of one edge of the tape and to which the coupling links or elements of the stringer are attached, and a relatively wide elastic or extensible portion integrally woven with and extending from said non-extensible portion in the direction of the other side edge of said mounting tape.

10. A separable fastener of the class described comprising stringers consisting of mounting tapes having coupling links attached to and spaced longitudinally of one edge portion of said tapes, said links being adapted to be coupled and uncoupled in the operation of the fastener, each stringer tape of the fastener comprising a body of fibrous material woven to form a uniform strong and durable non-extensible rib portion arranged longitudinally of one edge of the tape to which edge the coupling links of the fastener are attached, a relatively wide elastic or extensible portion integrally woven with and arranged longitudinally of the tape and extending from said non-extensible portion in the direction of the other side edge of said tape and that part of the non-extensible edge portion to which the links are attached being enlarged.

DAVIS MARINSKY.
